DEVICE FOR STACKING AND WRAPPING COINS

Earl W. Carper, Parkersburg, W. Va.

Application February 18, 1946, Serial No. 648,224

3 Claims. (Cl. 226—14)

1

This invention relates to improvements in collection receptacles and more particularly to coin stacking and wrapping devices.

One of the objects thereof is to provide a simple, efficient and inexpensive device which will facilitate the operation and labor of encasing coins of varying diameters in tubes also varying in diameters for the reception of said coins, in the act of stacking said coins in surmounted relationship so they may remain frictionally wrapped in said tubes.

Another object thereof is to provide a sturdy, reliable and easily manipulated coin stacker and wrapper based upon a principle that assures accurately registering tubes of varying diameters interchangeably with relation to a tube centering and holding unit, upon which the coins of varying diameters are stacked interchangeably.

A further object of this invention is to provide a device of the character described with means for holding a stack of progressively surmounted coins of the same diameter in under supported relation, as well as interchangeably so holding and supporting different stacks of coins of diameters different from the first stack of coins, as well as holding interchangeably the paper tube, appropriate in diameter for any particular stack of coins thus held and supported by it, so that the stack of coins may be encased in said paper tube effectively.

A further object of this invention is to provide means for spreading out coin wrapper tubes of interchangeably varying diameters so they readily present a sufficiently rigid bearing internally to progressively house a stack of coins of a common diameter, each tube in turn being so juxtaposed that it may be guided steadily as a longer surface is advanced around a growing stack of coins.

With the above and other objects in view my invention consists in the combination, arrangement and details of construction disclosed in the drawings and specification and then more particularly pointed out in the appended claims.

In the drawings, wherein similar reference characters designate similar parts throughout the respective views,

Figure 1 is a sectional elevation of my invention,

Figure 2 is a top plan view thereof,

Figure 3 is a plan view of my invention with the coin matching disks removed,

Figure 4 is a top plan view of a modified form of a part of my invention which variably supports coins of varying diameters,

2

Figure 5 is a fragmental sectional view of the parts of my modified invention,

Figure 6 is a cross section taken on line 6—6 of Figure 5, and

5 Figure 7 is a bottom plan view of a spreader device to be described.

Referring to the drawings, which are merely illustrative of my invention, I disclose the parts thereof. There is provided a flat rigid base member 10 having a flat bottom, and preferably a beveled circumferential edge 11. The base member is formed with a plurality of equally sized holes or sockets 12 marginally thereof at spaced apart points. Rising perpendicularly and centrally from the base member is a rigid pedestal or cylindrical rod-like post 19, its lower end being a reduced threaded shank 18 screw threaded in firmly anchored relation into the base member.

I provide a plurality of thick, elongated disk-like members of graduated diameters, designed to match accurately the diameters of coins of various common denominations such as pennies, nickels, dimes, quarters and fifty cent pieces, etc. These disk-like members are designated, for 20 example, 15, 15a, 15b, 15c, etc. according to varying diameters. Each member 15, 15a, etc. has a concentric depending screw-threaded shank or stem 13 of a diameter to admit of being easily slipped removably into any of the holes 12 in 25 the base member.

The disk-shaped members may be conical in cross section if desired, so as to taper upwardly, as shown in Figure 1. The upper end of the post 19 is flat and may also taper upwardly. An internally screw threaded bore 19a is formed centrally of the top of the post 19 which opens out of said top, which screw bore is of the same size as any of the holes 12 in the base member. It is designed to screw home any shank of any of 30 the disk-shaped members interchangeably into this bore at the top of the post for the purpose of firmly and removably anchoring same thereupon, thereby increasing the length of the post and at the same time variably increasing its 35 diameter where lengthened out, according to the particular disk member surmounted at its top at any particular time. The usual paper coin wrapper tubes which come in accurate internal diameters to accommodate encasingly pennies, nickels, dimes, etc. are employed in connection 40 with the foregoing invention. The tube is designated 35 and is placed in telescoping relation around the post 19 and may rest upon the base member.

45 In operation it will be seen that inserting the 50

55 In operation it will be seen that inserting the

shanks 13 of the disk-shaped members into the holes 12 of the base member is a convenient way to assemble them in varying sizes where they are readily accessible at all times to the operator. Knowing the particular coin he wants to wrap in a particular tube he selects one of the disk-shaped members which matches accurately in peripheral extent this particular coin. He also selects a paper wrapper tube that will snugly house a stack of the coins of this same denomination and diameter. This tube 35 he telescopes around the post, after he screws home the screw threaded shank 13 of this disk member into the screw bore 19a at the upper end of the post. Ordinarily the operator enlarges the diameter of the post along the thickness or length of the disk member surmounting its upper end. The opposite sides of each disk member are flat.

The operator fits the tube around the periphery of the disk member anchored on top of the post and draws the tube down so it encircles the post. Due to the larger diameter of the disk member thus encased by tube 35, there is clearance between tube and post, yet the post distends the lower portion of the tube that projects down over it, as well as guides the tube as it is fed along over the coins stacked up in the upper portion of the tube which projects beyond and above the post. One by one coins of the same denomination and diameter are supported upon the upper flat face of the disk member, which is of the same diameter as the coins at least at its lower end. By making the disk member conical in cross section, it will be obvious that less friction is set up between the paper tube and the disk member, the largest lower diameter of the disk member being the part that distends this tube. As the height of coins supported upon the disk member and on the post enlarges the paper tube is slid upwardly to accommodate same, the lower portion thereof always being guided against deflation by said post.

The use and application of the modified form of my invention will now be detailed. This device is illustrated in Figures 4, 5, 6 and 7 respectively. Here, it will be seen, that instead of employing separately sized disk members, and mounting them, when not in use, upon the base member 16, a unitary structure is devised consisting of preferably four radially arranged members collectively providing an expanding unit for a paper tube to be encased therearound.

Each of the radially arranged members is similar in form, shape and construction, consisting of the upright downwardly tapering portion 23 having flat flush upper ends 24 and downwardly inclining longitudinal edges 25, joining transversely disposed lower inclined edges 26 which incline in a direction counter to that of the inclined longitudinal edges 25 to form points 28 which rest directly upon the upper flat end of the post 19 as illustrated in Figure 5. The lowermost parts of the longitudinal edges 25 of these members 23 are formed with concave semi-circular recesses 27 immediately above the points 28 of these portions 23. Joining the inclined transverse edges 26 of the portions 23 are vertical edges 23a and formed at the lowermost ends of the last named vertical edges 23a are also semi-circular edges or recesses 33. There is a rigid sleeve 30 encircling the post 19, against the inner wall of which bear the inclined longitudinal edges 25 of the portions or members 23. A suitable resilient band preferably an elastic

band 29 is fitted and lodged in the circumferentially extending series of semi-circular recesses 27 of the members 23, pressing together their lower ends to vary the inclination of their longitudinal inclined edges 25. Before inserting the resilient band 29 into the set of semi-circular recesses 27 a non-resilient rigid small ring 34 will be inserted in the circumferentially extending series of semi-circular recesses 33 as shown in Figure 5, which will act as a prop for properly centering the members 23 in a radial series within the encircling sleeve 30. When the elastic resilient band 29 has been fitted into the mentioned series of semi-circular recesses and draws together the lower ends of the members 23, it is obvious then that they bear upon the ring 34 as upon a fixed pivot as this is accomplished, as each member and all members rock upon this ring 34.

In operation around those portions of members 23 shown in Figure 5, projecting above the sleeve 30, the paper coin wrapper tube is designed to be placed and inserted encasingly, the same paper tube being extended down the length of the post 19 so as to be distended and held spread out by said post in the act of stacking up coins in the upper section of the paper tube. When it is desired to adapt the device for supporting properly and centering accurately paper wrapper tubes of varying diameters to wrap correspondingly varying diameters of coins all it is necessary to do is to slide the sleeve 30 against the longitudinal inclined edges 25 of all of these members 23 whilst pressing down upon these members from their top edges 24 to hold them against displacement from the post. This will increase or decrease the size of the area presented collectively by the upper edges 24 of the members 23 accordingly as the sleeve 30 is slid in one direction or in a counter direction. When this sleeve 30 is slid downwardly of the post 19 the members 23 are unwedged thereby allowing the elastic band 29 to relax and contract so the lower parts of the members 23 contract and the upper coin supporting edges 24 expand in area. On the other hand, when the sleeve 30 is slid upwardly on the post, the edges 25 of members 23 are squeezed together, and they are wedged so they contract in area, whilst the elastic band 29 is forcibly expanded so the lower parts of members 23 expand.

What I desire to claim is:

1. A device as described consisting of a rigid base formed with a central upstanding post, any 55 of a series of paper tubes of graduated diameters and of the same length adapted interchangeably to be fitted around said post upon said base, said post being substantially the same length as said paper tubes, a frusto conical member resting 60 upon the upper end of said post effective to peripherally engage said tube when enclosed thereby and match its particular diameter so that coins of the same diameter as said tube may be stacked upon said member in said tube and said tube may be moved upwardly about said member and said coins.

2. A device for stacking and wrapping coins in paper tubes comprising a base, a cylindrical post fixed on said base and rising vertically therefrom of substantially the same length as said paper tubes, a frusto-conical disc, correlated means carried by said disk and the upper end of said post removably securing said disk thereon, the diameter of the divergent end of 75 said disk being greater than the diameter of said

post and substantially equal to the inside diameter of a selected paper tube, whereby said tube may be supported in distended telescoped relation to said post and slidable over said member for enclosing coins stacked on the reduced diameter upper end of said disk.

3. A device for stacking and wrapping coins in paper tubes comprising a base, a cylindrical post fixed on said base and rising vertically therefrom of substantially the same length as said paper tubes, about which the paper tube is adapted to be disposed for sliding thereon, a tube distending member at the upper end of said post, said member formed with divergent side edges, the divergent end of said member engaging the inner surface of said tube for supporting said

tube in distended position above said post, whereby said tube may be progressively slid upwardly from said post about said member and about coins supported on said member.
